Blake Hurt(57) **CLAIM**

The ornamental design for a scope tray, as shown and described.

DESCRIPTION

FIG. 1 is a top, front, right side perspective view of a scope tray showing my new design;

FIG. 2 is a top plan view thereof;

FIG. 3 is a left side elevational view thereof, the right side elevational view being a mirror image thereof;

FIG. 4 is a rear elevational view thereof, the front elevational view being a mirror image thereof;

FIG. 5 is a bottom plan view thereof; and,

FIG. 6 is a bottom, rear, right side perspective view thereof. The broken lines in FIG. 1 are for the purposes of illustrating the environment of the article only and form no part of the claimed design.
